UNITED STATES PATENT OFFICE.

GEORGE F. BALS, OF BROOKLYN, NEW YORK.

DESIGN FOR A CLUSTER-LIGHT FIXTURE FOR GASOLINE PUMPS.

Application filed November 30, 1928. Serial No. 29,076. Term of patent 14 years.

To all whom it may concern:

Be it known that I, GEORGE F. BALS, a citizen of the United States, residing at Brooklyn, county of Kings, and State of New York, have invented a new, original, and ornamental Design for Cluster-Light Fixtures for Gasoline Pumps, of which the following is a specification, reference being had to the accompanying drawing, forming a part thereof.

In the drawings accompanying and forming a part of this specification:—

Fig. 1 is a top view of this improved cluster light; and

Fig. 2 is a side view thereof.

I claim:

The ornamental design for a cluster-light fixture for gasoline pumps substantially as shown.

Signed at New York, N. Y., this 28th day of November, 1928.

GEORGE F. BALS.
